TEXTILE CONDITIONING PACKAGE

George R. Blake, Cumberland, Md., assignor to
Celanese Corporation of America, a corpora-
tion of Delaware

Application March 31, 1930, Serial No. 440,534

3 Claims. (206—46)

This invention relates to the conditioning of textile materials whereby the same are rendered more amenable to textile operations.

An object of my invention is to provide means for conditioning yarn while wound on a package by subjecting it to the vapors of a conditioning liquid. Other objects of my invention will appear from the following detailed description.

The conditioning of textile materials containing organic derivatives of cellulose presents a difficult problem, since such materials absorb but little moisture from the atmosphere. I have found that yarns, filaments or the like may be easily conditioned, either whilst in storage or in transit, by subjecting them to the action of vapors of a conditioning liquid which is generated from such liquid while it is contained in the interior of the yarn package.

In accordance with my invention I render textile materials, particularly those containing organic derivatives of cellulose, more suitable for textile operations by placing a liquid conditioning agent within the package on which they are wound. The whole package is then wrapped with a relatively impervious wrapping to prevent escape of the vapors.

The textile material to be conditioned may be in any suitable form, such as yarns, filaments, artificial straw or kristles and the like.

While this invention is of general application to textile materials of all kinds, it is particularly applicable to textile materials containing organic derivatives of cellulose examples of which are cellulose esters and cellulose ethers. Examples of organic esters of cellulose are cellulose acetate, cellulose formate, cellulose propionate and cellulose butyrate, while examples of cellulose ethers are ethyl cellulose, methyl cellulose and benzyl cellulose. The textile material need not consist wholly of organic derivatives of cellulose but may also contain other fibres such as natural silk, reconstituted cellulose, cotton or wool.

While I prefer to employ water as the conditioning agent, other suitable liquids may be employed, examples of which are volatile restricted solvents or swelling agents for the derivative of cellulose present. In the case of an acetone soluble cellulose acetate, examples of such restricted solvents or swelling agents are ethyl or methyl alcohol or aqueous solutions containing from 5 to 25% of acetone.

The yarn or other textile material is wound on packages such as cones, pirns, bottle bobbins and the like which have a hollow core.

The conditioning liquid may be absorbed in an absorbent material such as a sponge, raw cotton, infusorial earth and the like, and the same placed within the package.

The core of the package may be perforated so that the yarn may be subjected to the vapors of the conditioning liquid entering both through the interior and the exterior layer of yarn on the package. The core may be made of cardboard, metals such as aluminum, or the like, or plastic materials such as celluloid, bakelite, etc.

If the core upon which the package is wound is made of cardboard, as is the usual practice, in order to prevent collapse of the package due to the weakening action of the water used as the conditioning agent, it is preferable to insert a receptacle of such shape as to fit into the interior of the core. This receptacle is preferably perforated and is made of relatively strong and water-resistant materials, such as aluminum or other metals, or plastic compositions such as celluloid or bakelite.

After the insertion of the absorbent material containing the conditioning liquid, the yarn package is wrapped with a relatively impervious wrapping such as wax paper, parchmentized paper or cellophane, and ordinary precautions are taken to make an air-tight package, which will prevent the moisture from the absorbent material from evaporating into the atmosphere.

By my device, the yarn or other textile material is conditioned while it is in storage or while it is in transit. Moreover the textile material is kept conditioned until the very moment that it is being used.

Because of the action of the conditioning agent, textile materials treated by my invention are more suitable for textile operations. Thus in the case of yarn, the same may be knitted into a fabric having more wales and courses per unit length, which fabric is substantially free of distortions and pin holes. Such treated yarn may be more readily twisted. The knotting, bending and braiding qualities of bristles, straw and the like treated by my invention are improved.

For further improved results, suitable relatively non-volatile finishing agents or lubricants may be applied to the yarn either before or after it is subjected to the humidifying process. Examples of such finishes or lubricants are mineral oils, vegetable oils such as castor oil or olive oil, animal oil such as Neatsfoot oil, and softening agents such as glycol, diethylene glycol, glycine or any suitable mixtures of these ingredients.

In order further to explain my invention, but without being limited thereto, reference is had to the accompanying drawing, wherein

5 Figure 1 is a vertical cross section of a cone embodying this invention.

Figure 2 is a vertical cross section of a bottle bobbin showing another way of carrying out this invention, and

10 Figure 3 is a verticle cross section of a cone, showing a further modification of this invention.

Referring to Figure 1, a core 1, in the form of a cone, and made of metal, celluloid or bakelite, is provided with perforations 2. Upon this core 1, the yarn of cellulose acetate is wrapped to form the body 3. Within the core 1, a sponge 4 which has water absorbed therein is inserted. In order to make an air-tight package, the whole cone is wrapped in waxed paper or other impervious material as indicated at 5.

20 Referring to Figure 2, wherein a bottle bobbin package is shown, the core 10, made of cardboard or like material has perforations 11 therein. On this core 10, the yarn 12 is wrapped. An insert 13, closely following the configuration of the core 10, and made of metal, celluloid and the like, is inserted within the core. This insert 13 has perforations 14 that register with the perforations 11 of the core. The sponge 15 is inserted in the interior of the package, and this sponge has water or other conditioning liquid absorbed therein. The package is wrapped with the impervious wrapping 16.

30 Referring to Figure 3, which shows a package in the form of a cone, the core 20 is made of cardboard or like material. Yarn consisting of filaments of cellulose acetate is wrapped thereon as

indicated at 21. An insert 22 made of metal, celluloid and the like and having perforations 23 is placed within the core, and a sponge 24 containing conditioning liquid is inserted in the interior of the package. The package is wrapped with relatively impervious wrapping 25.

5 It is to be understood that the foregoing detailed description is given merely by way of illustration, and that many variations may be made therein without departing from the spirit of my 10 invention.

Having described my invention, what I desire to secure by Letters Patent is:

1. A textile package comprising a hollow core, at least part of the wall thereof being permeable 15 to vapor, yarn wound on said core around the permeable part thereof, an absorbent material wet but not saturated with a conditioning liquid within said core and a wrapper, impervious to the conditioning liquid, surrounding said yarn. 20

2. A textile package comprising a hollow core having holes through the wall thereof, yarn wound on said core, at least some of the holes opening against the yarn, an absorbent material wet but not saturated with a conditioning liquid 25 within said core, and a wrapper impervious to the conditioning liquid surrounding said yarn.

3. A textile package comprising a hollow core, at least part of the wall thereof being permeable to vapor, a perforated insert within said core, 30 yarn wound on said core around the permeable part thereof, an absorbent material wet but not saturated with a conditioning liquid within said insert and a wrapper, impervious to the conditioning liquid, surrounding said yarn.

35 GEORGE R. BLAKE.
